FIG. 1

FIG. 2

FIGURE 1 is a front view of a brassiere embodying by new design, and

FIGURE 2 is a rear view of the same brassiere.

The characteristic features of my design reside in the combination on the brassiere disclosed of the triangular net portions located at the inner ends of the cups and constituting a slightly contrasting continuation of the net portion along the upper inner half of each cup, one side of each triangle forming a substantial continuation of the lower inner line of each of the cups, an open space between the triangles and the connecting band, together with scalloping on the upper inner half of each cup, and a floral pattern parallel to the scalloping, all as shown.

I claim:

The ornamental design for a brassiere, as shown and described.
